UNITED STATES PATENT OFFICE.

WILLIAM A. BIGLER, OF CHICAGO, ILLINOIS.

DESIGN FOR A SPOON.

SPECIFICATION forming part of Design No. 22,094, dated January 3, 1893.

Application filed August 27, 1892. Serial No. 444,331. Term of patent 7 years.

To all whom it may concern:

Be it known that I, WILLIAM A. BIGLER, a citizen of the United States, residing at Chicago, in the county of Cook and State of Illinois, have invented and produced a new and original Design for Spoons, of which the following is a specification, reference being had to the accompanying drawing, which shows the front side of a spoon embodying the design.

Upon the bowl of the spoon is the representation of a pig. The tail of the pig is represented as passing through the bowl, near the junction of the bowl and handle, and as

partially encircling the lower part of the handle, the portion lying across the handle being looped, the essential and leading feature of the design being the representation of a pig arranged upon the bowl of a spoon, substantially as shown in the drawing.

What I claim is—

The design for spoons, substantially as herein shown and described.

WILLIAM A. BIGLER.
